E. A. LEWIS & P. R. PINKARD,
MUSIC LEAF TURNER,
APPLICATION FILED SEPT. 11, 1916.

1,244,749.

Patented Oct. 30, 1917.

UNITED STATES PATENT OFFICE.

EDGAR A. LEWIS AND PAUL R. PINKARD, OF ROSWELL, NEW MEXICO; SAID PINKARD
ASSIGNOR OF FOUR-TENTHS OF THE WHOLE RIGHT TO SAID LEWIS.

MUSIC-LEAF TURNER.

1,244,749.

Specification of Letters Patent. Patented Oct. 30, 1917.

Application filed September 11, 1916. Serial No. 119,467.

To all whom it may concern:

Be it known that we, EDGAR A. LEWIS and PAUL R. PINKARD, both citizens of the United States, residing at Roswell, in the county of 5 Chaves and State of New Mexico, have invented or discovered certain new and useful Improvements in Music-Leaf Turners, of which the following is a specification, reference being had therein to the accompanying 10 drawings.

This invention relates to leaf-turners for turning the leaves of books or sheet music, and has for its object the provision of a simple, compact, efficient, convenient, and generally improved device of this character so constructed and arranged as either to be readily portable or to be capable of being built into a book or music rest as a permanent part thereof, and when in place to serve 20 as a support for the book or music, said device being capable of operation to turn the leaves successively in either direction by the successive operations of one of a single pair of operating devices or members.

25 The foregoing and other objects of the invention, together with means whereby the same may be carried into effect, will best be understood from the following description of one form or embodiment thereof illustrated in the accompanying drawings, in which—

Figure 1 is a perspective view of a book or music rest or rack, showing the leaf turner in position thereon, and illustrating 30 the operation of the device.

Fig. 2 is a plan view with the cover of the casing removed.

Fig. 3 is a section on the line 3—3, Fig. 2.

Fig. 4 is a detail elevation, and

40 Fig. 5 a bottom plan view of the rotatable actuator.

Fig. 6 is an enlarged detail elevation of one of the leaf turning members or arms and its associated pinion.

45 Referring particularly to Fig. 1, 15 denotes a book or music rest which may be of any usual or well known form, either in the nature of a separate reading desk or music stand, or of the usual rack forming a part 50 of a piano, organ and the like. 16, Fig. 1, denotes the leaf turning device as a whole, which device may be either of a separate, portable character, or built in as an integral or permanent part of the book or music rest 55 15. The mechanism of the device 16 is enclosed within a casing which is relatively

flat in form, rendering the device readily portable when constructed separate from the music stand, thereby enabling the same to be carried about and used in connection with 60 any music rest, or, when built in as a permanent part of said book or music rest, occupying very little additional space and being not unsightly in appearance, said device serving, as will be seen, as a support for the 65 book or music 17, which rests upon the top thereof.

The casing aforesaid comprises a preferably rectangular body 18 and a cover 19, preferably detachably secured to said body, 70 as by screws 20. The upper edge of the casing body 18 and the lower edge of the cover 19 are cut away at the front to provide a slot 21 through which operate or swing the leaf turning members or arms 22, which may 75 be of any suitable number. Said arms or members 22 are provided at their outer ends with leaf-engaging portions 23 which extend above the casing in a position to engage the lower edges of the leaves of a book or 80 sheet music 17, the cover 19 being cut out at suitable points at the top, as at 24^a, to provide openings through which the leaf-engaging members or portions 23 extend. As 85 herein shown each of the members 23 comprises a pair of resilient arms adapted to receive between them the edge of a leaf.

Connected to or formed integral with each of the arms 22, is a pinion 24, the pinions of the series being rotatably mounted in co- 90 axial relation upon an upright stud shaft 25 secured to the bottom of the casing body 18. 26 denotes a second stud shaft, also supported in the casing body 18, and arranged with its axis parallel to the axis of the shaft 25. 95 Rotatably mounted on the shaft 26 is an actuator comprising a disk 27 and a gear member 28, said disk and gear member being permanently and rigidly connected, as by soldering or otherwise. The gear member 100 28 comprises a series of axially and circumferentially spaced gear segments 29 corresponding to the pinions 24, respectively, and adapted to engage and rotate said pinions successively as the actuator is rotated. In 105 order to insure the proper coöperation of the several gear segments 29 with their respective pinions 24, the actuator is held against longitudinal movement on the shaft 26, as by means of a spring 30 surrounding 110 said shaft, and bearing at its upper end against the cover 19 and at its lower end

against the gear member 28, whereby said actuator is held in its lowermost position upon said shaft. The disk 27 is provided on its lower side with a series of lugs or studs 5 31 corresponding in number and circumferential arrangement to the gear segments 29.

32 and 320 denote operating members for intermittently rotating the actuator. These 10 operating members being substantially similar in construction, only one will be described in detail. The member 32 comprises a lever pivoted at 33 to the bottom of the casing body 18. The lever 32 is normally held in the retracted position shown in Fig. 15 2 by means of a spring 34, and the forward movement thereof is limited by a stop lug 35. To further control, guide and limit the movements of the lever 32 there may, if desired, 20 be provided a keeper 36.

Pivoted at 37 to the free end of the lever 32 is a dog 38 normally held by a spring 39 against a stop lug 40. The construction is such that, as the lever 32 is swung forwardly 25 against the tension of the spring 34, the dog 38 will engage one of the lugs 31 on the disk 27 and turn the actuator through an arc corresponding to the length of one of the gear segments 29. As the lever 32 returns to 30 normal position under the influence of the spring 34, the dog 38 is permitted to turn upon its pivot 37 against the tension of the spring 39, and thereby pass the following lug 31 without turning the actuator back 35 from the position to which it has been advanced by the forward movement of the lever. In this manner successive oscillations 40 of the operating lever cause the actuator to be intermittently rotated, the amount of each rotation or step being substantially 45 equal to the circumferential spacing of the gear segments 29. The direction in which the actuator is thus rotated will depend upon which of the levers 32 or 320 is operated.

For operating or oscillating the levers or operating members as above explained, there are provided operating rods 41 and 410 pivotally connected at their inner ends to the 50 levers 32 and 320 respectively, and extending through suitably disposed openings in the front wall of the casing so as to be operable from the exterior thereof. The rods 41 and 410, particularly when the device 55 forms a permanent part of a book or music rest, may be operatively connected by any suitable or well-known means (not shown) to any suitable actuating members, such as foot pedals or knee levers. As illustrative 60 of means for operating these rods, said rods are herein shown as provided with push buttons 42 and 420, this arrangement being especially suitable for a portable device.

The complete operation is as follows:

The book or music 17 having been placed 65 upon the rack 15 and resting upon the top of the casing of the leaf turning device 16, the respective leaves to be turned are engaged with the leaf engaging members 23 of the several arms 22. For turning the leaves 70 from right to left in the usual succession the push button 42 is operated, and at the beginning of the operation all of the arms 22 which are connected with the leaves are 75 swung into the right hand position. Thereafter, at each operation of the push button 42, and consequent oscillation of the lever 32, the actuator will be turned through an arc corresponding to the spacing of the gear segments 29. As herein shown this arc is 80 substantially 90°, there being shown four each of the arms 22, pinions 24, gear segments 29, and lugs 31. At each turning movement of the actuator one of the gear segments 29 will engage and rotate its corresponding pinion 24, causing the arm 22 connected therewith to be swung from the right to the left hand position, carrying with it the leaf connected thereto. The arrangement is, of course, such that the arms 90 22 will be swung in the proper order to cause the leaves to be successively turned.

For turning the leaves from left to right, the push button 420 is operated to swing the arms 22 successively from the left to the 95 right hand position, the operation being exactly the reverse of that above described in connection with the push button 42.

Having thus described our invention we claim and desire to secure by Letters Patent: 100

A leaf turner comprising a casing, a series of leaf holding members extending above said casing, a co-axial series of pinions within said casing and connected with said members, respectively, an actuator within said 105 casing mounted to rotate on an axis parallel to the axis of said pinions and having a series of gear segments registering with said pinions, respectively, to engage and rotate said pinions successively as said actuator is 110 rotated, said actuator having a series of lugs corresponding in number and circumferential arrangement to said gear segments, a horizontally swinging lever pivoted within said casing and having at its end a pivoted 115 spring-pressed dog to engage said lugs successively upon successive oscillations of said lever and thereby intermittently rotate said actuator, a horizontally reciprocating rod connected to said lever and extending to the 120 exterior of the said casing, and a retracting spring for said lever.

In testimony whereof we affix our signatures.

EDGAR A. LEWIS.
PAUL R. PINKARD.
